William Bedle

UNITED STATES PATENT OFFICE.

WILLIAM BEDLE, OF KEYPORT, NEW JERSEY.

IMPROVED CRADLE.

Specification forming part of Letters Patent No. 55,227, dated June 5, 1866.

To all whom it may concern:

Be it known that I, WILLIAM BEDLE, of Keyport, county of Monmouth, and State of New Jersey, have invented certain new and useful Improvements in Self-Rocking Cradles for Children; and I do hereby declare that the following is a full, clear, and exact description of the construction and operation thereof, reference being had to the accompanying drawings, making a part of this specification, of which—

Figure 1 is a top view; Fig. 2, a side elevation; Fig. 3, a longitudinal section, and Fig. 4 a view of the operative mechanism.

This invention relates to a peculiar device for imparting to a child's cradle the swaying or lateral movements from side to side usually given by the hand or foot of the nurse when it is desired to put the child to sleep; and it consists of a kind of clock mechanism, (placed underneath the cradle and between the rockers,) which revolves a weighted arm that will throw its weight on either side of the cradle, alternately bearing the sides down, thus imparting to the cradle the desired rocking motion.

Having described the nature of my invention, I will now describe its construction and mode of operation.

In the drawings, A represents an ordinary child's cradle, with rockers B B. C is a box attached to the under side of the cradle containing the operative mechanism, which consists of a winding arbor or shaft, D, pivoted in the said box, and carrying a fusee or spiral spring, d and gear d', which impart motion through a train, E, to a pinion, F, said pinion actuating a weighted arm, G, carried by the

pinion-shaft f. This weighted arm G revolves in a circular casing, H, between the box C and the bottom of the cradle, and when it is desirable to stop the arm G, and thereby the rocking of the cradle, the brake I is thrown against a ratchet, K, on the pinion-shaft f, as shown in the drawings.

I would here remark that a winding-shaft and pinion may be placed at the end of the cradle, as shown in red lines, instead of the under side of the box C, if preferred.

The operation of my invention is as follows: The cradle being ready for reception of the child, I, by means of a key or crank L, wind up the fusee d d', and thus obtain the power to revolve the weighted arm G. I next remove the brake I from the ratchet K, when the weighted arm G will be revolved, and in revolving throw its weight on one side and then on the other side of the bearing-points of the cradle, said cradle, by its gravity, aiding the weighted arm in producing the desired rocking motion of the cradle.

Having described my invention, what I claim, and desire to secure by Letters Patent, is—

The weighted arm G, the brake I, and clock mechanism D E F, or their equivalents, when in combination with the cradle A, substantially as and for the purposes described and set forth.

In testimony whereof I have hereunto set my hand and signature.

WILLIAM BEDLE.
